Patented Aug. 13, 1968

211,953

AQUARIUM ORNAMENT OR THE LIKE

Willis J. Whittaker, 451 Nevada St.,
Toledo, Ohio 43605

Filed Jan. 25, 1967, Ser. No. 5,555

Term of patent 7 years

(Cl. D30—12)

Fig. 1

Fig. 2

Fig. 3

Fig. 4

Fig. 5

I claim:

The ornamental design for an aquarium ornament or the like, as shown.
